UNITED STATES PATENT OFFICE.

GEORGE A. STACKHOUSE, OF HAYWARD, CALIFORNIA, ASSIGNOR TO PACIFIC SPRING COMPANY, OF OAKLAND, CALIFORNIA, A CORPORATION OF CALIFORNIA.

BEDSPRING-SUPPORTING BRACKET.

Application filed February 23, 1924. Serial No. 694,593.

This invention relates to bed springs, and especially to an adjustable supporting bracket therefor.

The object of the present invention is to generally improve and simplify the construction and operation of brackets of the character described, and particularly to provide a bracket which is vertically adjustable to elevate or lower the spring with relation to the bed frame, and which is also laterally adjustable to take care of bed frames of various widths.

One form which my invention may assume is exemplified in the following description and illustrated in the accompanying drawings, in which—

Fig. 1 is a sectional view showing two positions of the bed spring supporting brackets.

Fig. 2 is a perspective view showing another view of the supporting brackets.

Practically all bed springs in use today, whether coil or fabric springs, are carried by an angle iron frame or the like such as indicated at A. Such frames consist of side rails 2 and end rails 3, the side rails 2 and end rails 3 supporting the springs whether they be coil springs or otherwise. A bed spring of this character when placed between the side sections of a bed does not always assume the desired elevation, and it does not always fit as the beds vary slightly in length and width.

The present invention shows a supporting bracket which is laterally and vertically adjustable. It consists of a piece of strap iron bent to form a flat section 4, a right-angular section 5, and a supporting foot or lug 6. There are four brackets employed and the side rails 2 of the spring supporting frame are slotted adjacent each corner as indicated at 7 to receive the brackets. The side rails are also provided with angle iron brackets such as indicated at 9, which are secured to the underside of the rails by rivets 8 or the like. The angle iron brackets are furthermore slotted as indicated at 10 to permit the flat section 4 of each supporting bracket to pass therethrough. A clamp screw 11 is also employed in connection with each angle bracket to permit lateral adjustment of the supporting brackets, and also to secure the same when in place.

If the supporting brackets assume the full line position shown in Fig. 1, the bed spring

will assume its highest elevation. By taking the brackets out and reversing them about their longitudinal axes so that they will assume the position shown by dotted lines in Fig. 1, the bed spring will be lowered to assume its lowermost position. By again removing the brackets and reversing their position end for end as shown in Fig. 2, an intermediate elevated position may be assumed and the outer end 2^a of the flat section 4 will then engage the side sections of the bed. The side sections of the bed are indicated at B and are usually provided with a foot ledge C upon which the supporting lugs or brackets rest.

The supporting brackets here shown permit adjustment, as far as elevation is concerned, and as they are slidably mounted in the slots 7 and 10 lateral adjustment is also permitted, thus taking care of beds of various widths.

The slotting of the frame and the angle brackets at the points indicated at 7 and 10 does not weaken the structure as the metal removed is amply taken care of by reinforcing action of the angle brackets. The clamping screws only serve one function, to-wit, that of securing the brackets when adjusted. No strain or load is transmitted to the screws and danger of jamming or bending of the screws, or stripping of the threads is thus obviated.

The brackets are readily applied to practically any form of spring supporting frame. They are cheap to manufacture, and they may be quickly adjusted both for vertical and lateral adjustment.

While the brackets here shown are more or less specifically illustrated, I wish it understood that various changes in form and proportion may be resorted to within the scope of the appended claims. I similarly wish it understood that the materials and finish of the several parts employed may be such as the experience and judgment of the manufacturer may dictate or various uses may demand.

Having thus described my invention, what I claim and desire to secure by Letters Patent is—

The combination with a spring supporting frame consisting of connected end and side rails and the side rails having slots formed therein adjacent each end, of a pair

of slotted angle brackets secured in each side rail in alignment with the slots in the side rails, a clamp screw carried by each angle bracket, supporting brackets extending through the slotted side rails and angle brackets and adapted to be engaged and secured by the clamping screws, said sup-

porting brackets comprising a straight main section and a bent offset foot extension, said brackets being reversible about their longitudinal axis and also end for end reversible, and said brackets being longitudinally adjustable.

GEORGE A. STACKHOUSE.
